UNITED STATES PATENT OFFICE.

GEORGE A. CLEMENT, OF MOUNT VERNON, NEW YORK, ASSIGNOR TO PATENT OPTICAL COMPANY, INC., A CORPORATION OF DELAWARE.

SET OF FUSED BIFOCAL-LENS BLANKS.

Application filed July 1, 1924. Serial No. 723,481.

To all whom it may concern:

Be it known that I, George A. Clement, a citizen of the United States, residing at Mount Vernon, in the county of Westchester and State of New York, have invented certain new and useful Improvements in Sets of Fused Bifocal-Lens Blanks, of which the following is a full, clear, and exact description.

10 My invention relates generally to the art of making fused bifocal lens blanks, that is, blanks formed by fusing a small piece of glass, known as a button or segment, in a countersink or depression in one face of a 15 larger or major piece of glass, the small piece of glass being of a higher index of refraction than that of the major piece of glass. Conveniently, the button is composed of flint glass and the major lens portion is 20 composed of crown glass. In blanks of meniscus or toric shape, the countersink is in the outer or convex face, and in finishing the blank to the desired lenticular form, this outer or bifocal side of the blank is given a 25 continuous spherical curvature, while the opposite face is finished to the requisite spherical or cylindrical form to satisfy the particular prescription. Although the bifocal side has a continuous curvature, the focal power 30 through the segment portion of the lens is greater than that of the major portion due to the higher index of refraction of the flint glass. The area of the lens occupied by the 35 segment or flint glass surface therefore comprises the near vision or reading field, while the major portion of the lens composed wholly of crown glass serves as the distance 40 vision field, and the difference in focal power between the two fields is known as the addition.

This added power through the reading field is determined both by the index of refraction of the flint glass and also by the curvatures of its faces. Since the finished 45 curvature of the outer face of the flint glass is the same as that of the major lens portion and since it has been the standard practice to finish this outer surface to one of a large 50 number of different curvatures in producing various lenticular powers for the distance field, it has been necessary to make the flint buttons with a wide range of curvatures to their inner faces in order to ob-

tain the desired addition for all bifocal prescriptions. 55

In accordance with my former invention patented in the United States in Letters Patent #1,494,889, of May 20, 1924, I proposed to obtain the various desired additions for a complete set of blanks by employing several different flint glasses of different indices of refraction, which enabled me to maintain the inner face of the button constant for all the blanks of the set, thereby not only materially reducing the number of 60 blanks which the dispenser must keep in stock, but also substantially reducing the manufacturing cost. According to the disclosures of that patent, the surface of the depression and hence the inner surface of 70 the flint button was preferably made plano, although it was explained that other geometrical forms might be employed for this surface.

The crown glass blanks in which the 75 countersink is formed are, as a rule, dropped or molded, a small percentage being plano, but nearly all being of meniscus shape. The latter have been molded to a variety of 80 curves, known as the base curves, the most common practice being to employ the 3-base curve system, namely, 3 diopters, 6 diopters and 9 diopters. The various base curves result in providing blanks which approximate the curvature which a lens grinder is called 85 to form on the faces of the blank in filling prescriptions, and therefore, by properly selecting his blanks the grinder is enabled to minimize the necessary grinding operation. It has been the practice, however, to depart 90 from these base curves in finishing both the outer and inner faces of the lens from the blank. The curvature of the outer face, for example, must be such as to effect the 95 desired addition, while that of the inner face must be such as to satisfy the prescription with respect to the lenticular power of the distance field. For instance, a blank 100 molded to a 9 diopter base curve might have its outer face finished to a 9.50 diopters to obtain the addition called for by the prescription, while its inner face might be finished to a -7 diopter curve. This would 105 be the case, for example, with a blank having a flint glass button of index 1.62 fused to a major crown glass lens of index 1.53

when the curvature of the countersink is -1.50 diopters and the prescription called for a correction of $+2.50$ diopters for distance and an addition of 2 diopters.

5 This necessity of finishing the outer face of the blank to a curvature different from the base curve was also characteristic of embodiments of my said former invention. In that case the outer finished curvature of the 10 lens must be such as to give the desired addition with the particular index of refraction of the flint glass incorporated in the blank, and it is, therefore, necessary with such a set of blanks for the lens grinder to 15 know the requisite curve for the bifocal face of the lens for each prescription, and grind the blank accordingly, the curvature of the minus or rear face being determined by the power of the distance field called for 20 by the prescription.

In the practice which has heretofore commonly prevailed in the manufacture and distribution of fused bifocal blanks, as above explained, as well as in the set of blanks 25 contemplated by my said former invention, the blanks are of necessity sold in their rough or entirely unfinished condition, since the lens grinder is called upon to impart various curvatures to the bifocal side of the 30 blank. My present invention is well adaptable to the practice of reducing the blanks to semi-finished form at the factory; that is, grinding and finishing the bifocal side of the lens, thereby requiring the lens grinder 35 to grind and finish only the inner face of the blanks to fill his prescriptions. It will be understood that this is preferable for several reasons, principally because more general uniformity of the finished product 40 is thereby assured, and also because the work which the dispenser is called upon to perform upon the blank is very substantially reduced.

It is a fact well known to optometrists 45 that certain relatively objectionable features of bifocal lenses are augmented with an increase in the added power. Besides more or less noticeable prismatic deviation through the reading portion of the higher additions, 50 there are frequently observable more or less chromatic aberration and internal reflection of the rays of light resulting, in effect, in a self-luminous medium through which the wearer looks and a constant diminution in his visual acuity. I have found that in the 55 case of fused bifocal lenses this is due to a considerable extent, at least, to the fact that in standard practice the increase in the power of addition is largely obtained by an 60 increase in the convexity of the inner face of the flint-glass button. In other words the countersink of the lenses of higher addition is a relatively deep concavity and the segment becomes a wide angle prism which is so 65 related to the eye of the wearer that the

visual axis is quite oblique to the inner face of the button. Consequently not only is there greater prismatic deviation, but the chromatic aberration is intensified and the rays of light which coincide with the visual 70 axis are at a decided angle to the radius of curvature of the inner face of the button and hence are reflected back and forth between the two surfaces of the button and, have the effect of internally illuminating 75 the flint glass.

By my invention I am able to minimize these undesirable effects by properly shaping the button and relating it to the visual 80 axis. My invention, briefly stated, resides in so relating the index of refraction of the button and the outer curvature of the lens that the countersink is in no case a concavity, but is always a plus curve. The set of lens blanks comprehended by my invention are 85 composed of a plurality of series according to the finished curve on the bifocal side. This curve increases in power from series to series and is sufficiently great for every 90 series so that the lens blank of highest addition in every series has a countersink, the surface of which is a plus curve. I have found that the absence of minus countersinks greatly improves the lenses in the respects referred to above. The perisopic 95 shape of the button makes it possible to dispose it more nearly concentric with the eye-ball, and it will be appreciated that true 100 concentricity is more nearly realized with each higher series since the radius of the outer finished curve becomes shorter from 105 series to series toward the higher additions, thereby approaching coincidence of the visual axis with the radius of curvature of the inner face of the button toward the high 110 additions where the objectional features are most pronounced in fused bifocal lenses as heretofore made. A further advantage of my invention is the fact that the lenses may be made thinner than is possible with blanks 115 in which the button is bi-convex.

Another feature which is rendered possible by my invention and which my invention contemplates, is the employment of what is known as a wide angle segment. 120 Heretofore, in fused bifocal blanks made according to the standard practice, the diameter of the segment has been limited because of the fact that the thickness of the segment has been proportional to the size, 125 since practically all the segments have plus curvatures for their inner faces. Therefore, if the segment were larger than 25 mm. in diameter, the finished lenses would be too thick and consequently too heavy, at 130 least for the higher additions, since manifestly the inner side of the blank could not be ground down so as to wear away any of the inner face of the segment. The standard crown blank is substantially 50 mm. 135

in diameter, and the diameter of the segment of fused bifocal lenses has, therefore, been limited to substantially one-half the diameter of the crown blank, part of the segment and of the crown glass being, of course, finally removed in cutting out the lens. Since with my invention the flint glass segments are all concavo-convex in form, the thickness of the segment does not vary greatly with the addition and I am, therefore, able to use segments substantially greater than one-half the diameter of the crown blank.

I shall now more particularly explain my invention in connection with the appended drawings and shall thereafter point out my invention in claims:

Fig. 1 is a face view of a rough molded crown blank;

Fig. 2 shows in section four such blanks molded to, respectively, 6, 8, 10 and 12 diopter curves;

Figs. 3 and 4 are views similar to those of Figs. 1 and 2, after the countersink has been formed in the blank;

Figs. 5 and 6 are, respectively, a face view and section of a flint button ready to be fused into the countersink;

Fig. 7 is a sectional view of the rough blank after the fusing operation;

Fig. 8 is a section of the blank in semi-finished form, that is, after the bifocal surface is finished;

Fig. 9 is a table giving for the respective additions the curvature of the countersinks and the finished curves on the bifocal side of one set of blanks embodying my invention;

Fig. 10 is a similar table for another embodiment of my invention;

Fig. 11 is a similar table showing how my invention may be embodied in a set of blanks including not only those of Fig. 9 but several alternative numbers for most of the additions.

The crown glass blank 1 is formed by heating a sufficient quantity of glass to plastic condition and then molding it to the desired curvature. As an illustration, I shall explain my invention as embodied in a set in which the finished curve on the bifocal side for the several series is, respectively, 6 diopters, 8 diopters, 10 diopters and 12 diopters. In order to facilitate the formation of these curvatures on the blanks of the respective series, the blanks 1 will be molded, some to the 6 diopter curvature of the blank 1^a of Fig. 2, some to the 8 diopter curvature of blank 1^b of Fig. 2, some to the 10 diopter curvature of blank 1^c of Fig. 2, and some to the 12 diopter curvature of blank 1^d of Fig. 2. Thereafter, there is ground from near the center to one edge on the convex face of the blank 1 countersink 2, the curvature of which will

depend upon which particular blank of the series is to be made, that is, upon the addition, as will be later explained in connection with Figs. 9, 10 and 11. A segment 3 of flint glass is then formed of a diameter 70 substantially greater than one-half that of the crown blank 1. For example, if the diameter of the blank 1 be 50 mm., that of the segment 3 may be 30 mm. The segment 3 is then fused in the countersink 2 in accordance with the well known practice, as shown in Fig. 7 and thereafter the outer face is ground down and finished, as shown in Fig. 8. As above explained, it is a characteristic 80 of my invention that this outer face is finished either to a 6, 8, 10 or 12 diopter curve in the illustrated instance, according to the series to which the blank belongs, and that there is no departure from these selective curvatures.

I have shown in Fig. 9 one way in which my set may be made up for additions ranging from .25 diopters to 3.75 diopters, within which range come practically all of the prescriptions that a dispensing optician is called upon to fill. The flint glass for this set, as well as for all the sets which I have illustrated and will hereinafter describe, has an index of refraction of 1.6973, and this flint glass, when fused to crown glass having an index of refraction of 1.53 will add 95 1 diopter in power when its plano-convex curvature is 3 diopters.

It will be seen that the set illustrated in Fig. 9 is divided into four series having 100 their bifocal side finished, respectively, to plus curves of 6 diopters, 8 diopters, 10 diopters and 12 diopters.

The first five units of the series are comprised in the 6 diopter series. Since the 105 first unit has an addition of .25, that is $\frac{1}{4}$ of a diopter, the focal power of the flint button must be $\frac{1}{8}$ that of a plano convex button having a curvature of 6 diopters, since such a plano convex button would add 110 2 diopters. That is obtained by making the inner face of the flint button a -5.25 diopter curve. The difference then between the front and rear faces in dioptic power is +.75 diopters, which is $\frac{1}{4}$ of 3 diopters 115 and hence will add $\frac{1}{4}$ of a diopter. So it will be seen that the power of addition for the succeeding units of the 6 diopter series is increased successively $\frac{1}{4}$ of a diopter by subtracting .75 diopters from the curve of 120 the countersink, that is, from the minus curve on the inner face of the button, making a plus curve of 2.25 diopters for the countersink of the 1.25 addition unit, which is the highest addition for the 6 diopter 125 series in this particular set. The next three units of the set are comprised within the 8 diopter series. In order to give an addition of 1.50 diopters the effective curvature of the button must be +4.50, which is obtained by 130

making a +3.50 curvature to the countersink, and similarly it will be seen that countersinks of +2.75 and +2.00 diopter curves will give additions of 1.75 and 2.00 diopters with the finished curve of 8 diopters on the bifocal side of the blank.

The next two numbers in this particular set are included in the 10 diopter series, and it will be seen that a +3.25 curvature of the countersink will give an effective curvature of +6.75 diopters to the button which will result in an addition of 2.25 diopters. Similarly, it will be seen that a plus curvature of 2.50 diopters for the countersink will 15 give an effective curvature of +7.50 for the button, or an addition of 2.50 diopters.

The last five units of the set are comprised within the 12 diopter series and by computation it will readily be seen that the countersink curvatures indicated in the table 20 of Fig. 9 for the 12 diopter series will give the respective additions there indicated.

It is apparent that other values might be selected for the finished curves of the bifocal side of the blanks of the several series and that the several series might be otherwise apportioned throughout the range of successive additions in such a manner as to have all of the countersinks of plus curvatures. Another plan is illustrated, for example, in Fig. 10 in which I have shown how the set might be made up of 5 series having for their bifocal side finished curves of, respectively, 4, 6, 8, 10 and 12 diopters. It will readily be seen that the first unit 35 has an effective curvature of +.75 for the button and hence an addition of .25 diopters. In a similar manner it will be seen that each countersink curvature indicated in the 40 second horizontal row of Fig. 10 will, with the indicated finished curves on the bifocal side, give the respective additions indicated in the first horizontal row of that figure.

In Fig. 11, I have consolidated in one table various alternative blanks for the several additions, all of which have plus countersinks. This illustrated set comprises only the 6, 8, 10 and 12 diopter series for the finished curves of the bifocal sides, but it is manifest that a 4 diopter series could be added thereto, or that other curvatures might be employed for the several series. In the set illustrated in this table there are a plurality of units for all of the additions up to 3.25 diopters, there being four each for the first seven additions, three each for the next three additions, two each for the next three additions, and one for each of the last two additions. The advantage in such a multiple set is the fact that it gives the lens grinder greater latitude with respect to his tool equipment. While, for example, he might be unable with his tools to fill a prescription from one of the units for a certain addition, he would be able to do so from

some other unit having that addition. In the first horizontal row of this table of Fig. 11 is given the respective additions, as in Figs. 9 and 10; and in the succeeding horizontal rows are given first the finished curve 70 of the bifocal side of the blank and thereafter the curves of the countersinks, which will give the respective additions appearing at the top of the columns. It will be noted that all of the countersinks of this table are plus curves. It will be understood that, if desired, a flint glass having a higher index of refraction might be used for the numbers which would be placed in the blank spaces so as to give plus countersinks according to my invention.

It is obvious that my invention is not limited to the finished curvatures for the bifocal face of the blanks which I have selected for illustration, nor to the particular index of refraction for the flint glass which I have given in my explanation above and that various other respects in which the numbers may be changed from that illustrated in the tables of Figs. 9, 10 and 11, will readily occur to those skilled in the art within the scope of my invention.

I claim:

1. A product in the manufacture of bifocal lenses that have their entire bifocal sides finished entirely to continuous curves, comprising a set of bifocal lens blanks progressing from lowest to highest addition and each formed by fusing a small piece of glass having a relatively high index of refraction into a plus countersink in the plus side of a major piece of glass of lower index of refraction, the set being made up of a plurality of series classified according to the finished curve on the bifocal side, the curve being the same for all the blanks of each series but different for the several series, and each series being made up of a plurality of units of progressively higher additions.

2. A product in the manufacture of bifocal lenses that have their entire bifocal sides finished entirely to continuous curves, comprising a set of bifocal lens blanks progressing from lowest to highest addition and each formed by fusing a small piece of glass having a relatively high index of refraction into a plus countersink in the plus side of a major piece of glass of lower index of refraction, the set being made up of a plurality of series classified according to the finished curve on the bifocal side, the curve being the same for all the blanks of each series but different for the several series, and each series being made up of a plurality of units of progressively higher additions, characterized by the fact that the small pieces of glass throughout the set are of the same index of refraction and the said index and the curvature of the bifocal side 120

of the units of each series are so related that the surface of the countersink of the unit of highest addition of each series is a plus curve.

- 5 3. A product in the manufacture of bifocal lenses that have their entire bifocal sides finished entirely to continuous curves, comprising a set of bifocal lens blanks progressing from lowest to highest addition
10 and each formed by fusing a small piece of glass having a relatively high index of refraction into a plus countersink in the plus side of a major piece of glass of lower index of refraction, the set being made up of a
15 plurality of series classified according to the finished curve on the bifocal side, the curve

being the same for all the blanks of each series but different for the several series, and each series being made up of a plurality of units of progressively higher additions, 20 characterized by the fact that the diameter of the small pieces of glass is substantially greater than one half that of the major pieces and the index of refraction of the small pieces of glass and the curvatures of 25 the bifocal side of the units of the several series are so related that the inner faces of all the small pieces of glass are concave.

In witness whereof, I hereunto subscribe my signature.

GEORGE A. CLEMENT.
